UNITED STATES PATENT OFFICE.

FRED M. DAVIS, OF CHICAGO, ILLINOIS, ASSIGNOR TO PULLMAN COUCH COMPANY, OF CHICAGO, ILLINOIS, A CORPORATION OF ILLINOIS.

SOFA-BED.

1,194,330.

Specification of Letters Patent.

Patented Aug. 8, 1916.

Application filed May 15, 1913. Serial No. 767,782.

To all whom it may concern:

Be it known that I, FRED M. DAVIS, a citizen of the United States of America, and a resident of Chicago, county of Cook, and State of Illinois, have invented certain new and useful Improvements in Sofa-Beds, of which the following is a specification.

This invention relates to foldable sofa beds of the class in which a series of sections are adapted and arranged to unfold outwardly and forwardly to form a bed the length of which is transverse to the length of the sofa, and which is of ordinary shape and size.

The main objects of this invention are to provide an improved sofa bed of this kind in which the frame of the seat member of the sofa shall constitute the middle major section of an open perimetrical bed frame adapted to provide for free movement of the bed spring; in which two bed sections back of the seat member and constituting the head portion of the bed frame shall be automatically locked and held in their elevated position when raised to form a bed and shall be released automatically when the adjacent forwardly disposed or seat section is raised for folding; in which the sections when extended shall constitute a substantially rigid and continuous open frame adapted to support a bed spring formed of resilient metal fabric, as linked or woven wire, or of similar construction stretched across the frame; in which the seat member shall be hinged to the front of the housing and arranged to coact with a rearwardly and downwardly disposed frame member to raise the same to a horizontal position when the seat is swung forward in alinement therewith and rotated to its bed position; and in which the seat member and adjacent head section shall be strongly equipped and arranged for coaction to swing together in rigid alinement for lifting the head section into place when the seat and foot sections carried thereby are swung outwardly and downwardly into place.

A specific embodiment of this invention is illustrated in the accompanying drawings, in which—

Figure 1 is a plan view of the sofa bed in its extended position for use as a bed, the mattress and bedding being removed. Fig. 2 is a longitudinal vertical section taken on the line A—A of Fig. 1. Fig. 3 is a section also taken on the line A—A of Fig. 1 but

with the parts folded and with the bedding in place. Fig. 4 is a transverse vertical section on the line B—B of Fig. 1.

In the construction shown in the drawings the sofa bed comprises a relatively long and narrow housing 5 adapted to fit with its back close against the wall both when folded and when extended, said housing having ends 6 and back 7. A seat member 8 is pivotally mounted at its forward edge between the ends 6 to the front edge of the sofa and has one side thereof upholstered to form a sofa seat 9. The opposite or reverse side of the seat member is formed and adapted to serve as one section of the bed, the arrangement of the sections being such that this seat member constitutes the middle major section of the bed.

A head minor section 10 is also pivoted at one edge to the front of the sofa and is arranged for coaction with the said seat section in unfolding the bed. Said seat and head minor sections may be pivoted to the housing by the same hinge pintles 12. A short foot minor section 13 is pivoted to the free edge of said seat section. A head major section 14 is pivoted to the free edge of the said head minor section and a foot major section 15 is pivoted to the oppositely disposed or foot minor section 13, thus constituting a bed frame having three major sections 8, 14 and 15, and two intermediate minor sections 10 and 13, making five in all. The said bed sections are formed and arranged so that when unfolded they provide a rectangular open bed frame, the lateral members or side rails 16 of which are held spaced apart by the head and foot rails 17 and 18 respectively at the ends and by the horizontal or cross frame member 19 of the seat frame at or adjacent to the center. By this arrangement the side rails are held spaced apart and rigidly braced against the tension of the bed spring with the use of only one transverse brace or bridging member intermediate of the ends, this member being an integral part of the seat frame. The side rails of the seat section are preferably formed as vertical sides of the seat frame and are arranged to project upward when the seat section is in its bed position, and adapted to support the sides of the bed spring, said frame being open at the ends to provide clearance for said spring.

The seat frame is made substantially in-

tegral and rigid and of sufficient depth to avoid interference of the seat portion proper constituting one side, with the bed spring 20 attached to the opposite side, the seat cross member having substantially a U-shape, so disposed that when the frame is unfolded the transversely disposed portion of the U-member is carried well below the spring, thus leaving an open space between the upwardly turned ends for free movement of the bed spring.

Foldable means of suitable form are provided to support the foot portion of the bed. For this purpose legs 22 may be pivoted to opposite sides of the foot and middle major sections at points adjacent to their outer ends, said legs preferably being arranged and connected by any suitable means to fold automatically, as by means of links 23 connecting the upwardly projecting ends of the legs with the adjacent inwardly disposed minor sections respectively.

The several frame sections are all foldably connected or hinged together by a form of rule-joint, except at the point where the seat section and the head minor section are hinged to the front edge of the housing. A form of leverage joint is provided at this point on each side of the frame, one of the sections being provided with a rigid substantially integral portion or member arranged to overlap the coacting adjacent section for engagement therewith when they swing into alinement in unfolding. The said leverage member preferably consists of a rigid bar 24 formed substantially integrally with or attached to the stationary pivot end of the head minor section 10 in alinement therewith, and the seat section is provided with an outstanding stud or lug 25 adapted to engage with said bar 24 when the seat is swung into alinement therewith. This leverage bar may be long and heavy enough to provide great leverage strength and still not be so long as to project beyond the upper surface of the seat upholstering when the sections are folded as indicated in Fig. 3.

The rule-joint connecting the head major and minor sections 14 and 10 is arranged to fold downwardly and is reinforced by means of a bar 27 secured to the under side of the minor section and arranged to lap under the head major section, thus providing great lifting strength.

Means are provided in the rear of the housing for automatically engaging the free end of the head major section when it is raised to its horizontal position, said means comprising one or more rearward yieldable locks or spring catches 28 of the nature of a latch, adapted and arranged to be pressed back by the bed section in rising to its horizontal position, the catch then springing forward into its normal position to prevent the

section from swinging down until the seat section is again raised for folding the bed. The forward movement of the latch is limited by a stop 29 overlapping its lower tip, thus assuring release of the bed section therefrom as soon as the head sections are folded to a certain degree, sufficiently to withdraw the head major section forwardly and away from the latch.

When the seat section is raised for folding the bed the adjacent ends of the said head sections will be free to fold and move downwardly by gravity. A slight movement in this direction suffices to draw the head major section forwardly enough to release from the said catch 28, leaving it free to drop into alinement with the adjacent minor section, which relative position it will maintain during the folding movement until the said head major section comes to a bearing on the lower part of the housing frame, as upon the cross beam 30, whereupon the joint connecting the same to the minor section will flex and the minor section 10 will gradually swing into a substantially vertical position and the head major section will take a substantially horizontal position.

Suitable limiting means as shoulders or stops 31 are provided on the sofa housing adjacent to the back to support the rear or non-pivoted edge of the seat section 8 and the other members carried thereby when the bed is folded. These stops 31 also serve to definitely arrest the upward swing of the head major section 14 as soon as it reaches the point where engaged by the catch 28. Corresponding shoulders 32 and 33 are provided on the said seat and head sections to engage the upper and under sides respectively of the stops 31. The seat shoulders 32 are positioned adjacent to the cushioned side in order that the single pair of stationary stops 31 may serve as stops for both the head and seat sections.

When the foot major section is folded upon the seat section it may be held in place to prevent swinging out of position by any suitable means, as hooks 33.1 pivoted on each side.

Assuming that the sections are folded with the seat in its normal sofa position, the bed may be unfolded by grasping the rear edge of the seat member and swinging it upwardly and forwardly until it comes to a substantially vertical position, at which point the leverage member 24 on the adjacent minor section will engage the pin 25 on the seat member, whereupon continuance of the outer turning of the seat member will serve to rotate the head minor section in alinement with the seat member. As the motion is continued the rear end of the head major section will slide rearwardly and its hinged edge will be raised until it comes into alinement with the head minor section,

whereupon the seat and head sections will swing together in alinement until they come to their horizontal bed position, and the catch 28 engages the rear edge of the head major section. The seat supporting legs are unfolded automatically by this operation. The foot major and minor sections are then unfolded by simply swinging them upwardly and forwardly to their horizontal position. The foot supporting legs are likewise unfolded automatically when the foot sections are unfolded.

In folding the device the foot sections are first folded upon the seat section, the outer legs being automatically folded therewith. The hooks 33.1 are then engaged to hold the seat and foot sections together when the seat section is turned. As the seat section is raised the head sections 10 and 14 are thereby permitted to flex downwardly, thus withdrawing and dropping section 14 from the catch 28, the said head sections folding by gravity independently of the lever and catch mechanism 24—25, and the seat section is turned to its normal seat position, as shown in Fig. 3.

Although but one specific embodiment of this invention has been herein shown and described, it will be understood that numerous details of the construction shown may be altered or omitted without departing from

the spirit of this invention as defined by the following claim.

I claim:

A sofa bed, comprising a frame, a foldable sectional bed bottom mounted thereon including a seat section, an inner section, and a connecting section having rule joint connections, the pintles for which are each in substantially the same plane as the bed bottom when unfolded, said bed bottom being turnably connected to the front part of said frame adjacent to the joint for the connecting and seat sections, a resiliently yielding outwardly movable stop on the back part of said frame for supporting said inner section in its bed position, said stop having a guide face inclined inwardly and upwardly for coaction with said inner section in unfolding whereby said stop is retracted, and an upwardly facing part or seat adjacent to the upper end of said face to receive and support the coacting part of said inner section when the latter is raised sufficiently to permit said stop to spring inward thereunder.

Signed at Chicago this 10th day of May, 1913.

FRED M. DAVIS.
